Attorney

UNITED STATES PATENT OFFICE.

BENEDETTO P. SIMONE, OF PROVIDENCE, RHODE ISLAND.

RAZOR-BLADE SHARPENER.

Application filed June 16, 1922. Serial No. 568,721.

To all whom it may concern:

Be it known that I, BENEDETTO P. SIMONE, a citizen of the United States, residing at Providence, in the county of Providence and State of Rhode Island, have invented certain new and useful Improvements in Razor-Blade Sharpeners, of which the following is a specification.

My invention relates to a razor blade sharpener of the rotary type and has for its essential objects, compactness, strength, sightliness, adaptability for use with blades of different types and sizes, facility of operation, convenience for reversal of the blade, and means for applying a uniform pressure of the blade against the sharpening element.

To the above ends essentially my invention consists in such parts and in such combinations of parts as fall within the scope of the appended claim.

In the accompanying drawings which form a part of this specification,

Figure 1 is a top plan view of my novel device,

Figure 2, a side elevation of the same showing a portion of the side wall thereof broken away,

Figure 3, an end elevation of the same,

Figure 4, a section of the plate holder and attaching plate taken on line 4—4 of Figure 1.

Like reference characters indicate like parts throughout the views.

In detail my device consists of an oblong box 6 having an open top, and comprises side walls 7, end walls 8, and a base 9. The walls have ornamental corner plates 10 fast to and covering the corners of the box. Journaled in the side walls is a transverse shaft 12 rotatable by a crank, pulley, or otherwise. In this instance a grooved pulley 13 is shown as the driving element. In the side walls also are lubricating holes 14 extending from the admission plates 15, fast to the top faces of the walls, to the shaft. Fast to the shaft is a solid broad wooden roll 17 located between the walls and projecting slightly above the same, whose periphery is covered by a band 18 of leather or other stropping or abrading material.

An upright 20 is fixed to one end wall,

In this case it is seated in a rectangular recess 21 in the end wall, and recesses 22 in the side walls. An attaching plate 24 is fixed to the upright by screws 25 and has integral with its lower end hooks or hinge sleeves 27 embracing a pintle 28. A pair of clamping plates 30 are provided with integral resilient arms 31 at their rear ends connected by an end loop 32 embracing the pintle. The clamping plates are thus pivoted upon the described hinge structure. These plates are strengthened, their clamping action enhanced, and capacity for shouldered blades afforded by reason of transverse swells 34 near their free ends. A clamping screw 36 passes through perforations 37 in intermediate portions of the plates. The screw head 38 is below the plate, and upon the screw above the plates is threaded a clamping nut 40.

The plates 30 are normally held downwardly into close contact with the peripheral covering 18 of the roller by a helical spring 42 fast at one end to the screw 36 between the screw head and plates, and at the other end to a hook or pin 44 in the wall 8 below the upright.

In Figure 2 is shown a safety razor blade 46 carried between the plates 30 and bearing against the band 18 of the roll 17, whereby sharpening or stropping is effected by rotation of the latter.

I claim:

In a razor blade sharpener, a box, a driving shaft rotatably mounted in the box transversely thereof, a roll fast to the shaft within the box and projecting slightly above the box, a peripheral band of stropping material upon the roll, an upright upon one end of the box, an attaching plate fixed to the upright, hinge sleeves upon the attaching plate, a pintle in the sleeves, clamping plates, a resilient loop integral with the clamping plates and embracing the pintle between the sleeves, a clamping member engaging an intermediate portion of the plates, and a spring supported by an intermediate portion of the plates and fast to the box below the pintle.

In testimony whereof I have affixed my signature,

BENEDETTO P. SIMONE.
